Inventor
J. W. Wetzel,

By *Clarence O'Brien*
Attorney

UNITED STATES PATENT OFFICE.

JOHN W. WETZEL, OF ALLENTOWN, PENNSYLVANIA.

FIRE ESCAPE.

Application filed April 21, 1926. Serial No. 103,535.

This invention relates to a fire escape comprising a novel form of flexible ladder which is normally arranged within a special casing constructed to be anchored to the 5 wall of a building directly beneath a window in order that ready access may be had to the ladder to permit the occupants of the building to escape during a fire.

One of the primary objects resides in the 10 provision of a ladder containing casing that is so constructed that the same will automatically swing to open position when the lid thereof is raised and at the same time permit the ladder to drop to fully extended position.

Other objects will become apparent as 20 the nature of the invention is better understood, the same comprising the novel form, combination and arrangement of parts hereinafter more fully described, shown in the accompanying drawing and claimed.

In the drawing:—

Figure 1 is a front elevation of a fire escape constructed in accordance with the 25 present invention, the same being shown in position for use.

Figure 2 is a view disclosing the casing above referred to in closed position and within which is mounted said folding ladder, and

Figure 3 is a transverse section taken through the fire escape as illustrated in Figure 2.

Now having particular reference to the 35 drawing my novel fire escape comprises a sheet metal receptacle that includes a back wall 5 that is adapted to be anchored to the wall of a building A directly beneath a window B thereof. Hingedly secured to the 40 opposite vertical edges of said back wall are the side walls 6—6 of the casing that are cut as shown at 7 for receiving the outer sill C of the window frame, the length of said walls being such that the upper edges 45 thereof will engage flush with the edge of the sill. At the forward edges of the side walls the material comprising the same is bent inwardly at right angles in order to provide the front walls 8—8 of the casing; the edge of one wall section is bent into right angular form as shown in Fig. 3. Moreover, a strip of metal 9 is secured to this section adjacent the bent edge to allow the complementary edge of the other front 55 wall section to fit between the strip and the bent portion as illustrated plainly in Fig. 3.

Hingedly secured to the lower edge of the back wall 5 is a bottom wall 10, the side and front edges of which are adapted to rest upon flanges 11 formed at the lower edges 60 of the side and front walls of the casing to support the bottom wall in horizontal position when the side and front walls are closed as disclosed in Figures 2 and 3.

Anchored to the front side of the back wall 5 adjacent the upper end thereof is a strip of spring steel 12, the ends of which extend beyond the edges of the wall and are curved slightly forwardly for frictional engagement with the inner sides of the walls 6—6 for normally forcing the same outwardly to the position shown in Figure 1. The casing further embodies a slip type lid 13 for arrangement over the upper open end 70 of the casing when all of the walls have been moved to closed position, and for maintaining the side walls closed against the action of the spring 12.

Extending forwardly from the rear wall 5 of the casing at the upper end thereof is a bail like horizontally arranged member 14 to the side legs of which are connected depending metallic arms 15—15 to which is connected one end of a conventional form of folding ladder 16 which when in folded condition is adapted for storage within the casing but which will drop to the open position of Figure 1 when the casing is open, it being clearly understood that by removing the lid 13, the casing will immediately 80 move to open position and the ladder under its own weight will drop to the extended position in Figure 1.

Minor changes may be made in the invention without affecting the spirit and scope of the appended claims.

Having thus described the invention, what I claim as new and desire to secure by Letters Patent is:—

1. In a fire escape of the class described, a foldable ladder and a casing therefor, said casing comprising a back wall adapted to be rigidly secured to a part of a building, combined side and front walls hingedly connected to the back wall, a bottom hingedly connected to said back wall, means on the side and front walls for supporting said bottom in casing-forming relation, and a removable cover having a marginal flange adapted to embrace the side and front walls for maintaining all of the walls of the casing in ladder enclosing position.

2. In a fire escape of the class described, a foldable ladder and a casing therefor, said casing comprising a back wall adapted to be rigidly secured to a part of a building, combined side and front walls hingedly connected to the back wall, a bottom hingedly connected to said back wall, means on the side and front walls for supporting said bottom in casing-forming relation, and a removable cover having a marginal flange adapted to embrace the side and front walls for maintaining all of the walls of the cas-
- ing in ladder enclosing position, said ladder being connected to said back wall, and a flat spring connected to said back wall and having its end portions engaging said side walls, whereby when the cover is removed, said side walls will be forced outwardly and away from each other to allow the casing to open and to permit the ladder to drop down to operative position.

In testimony whereof I affix my signature.

JOHN W. WETZEL.
